UNITED STATES PATENT OFFICE.

LARS L. FURAN, OF THIEF RIVER FALLS, MINNESOTA.

SANITARY SEAT COVER.

Application filed September 22, 1921. Serial No. 502,393.

To all whom it may concern:

Be it known that I, LARS L. FURAN, a citizen of the United States of America, residing at Thief River Falls, in the county of 5 Pennington and State of Minnesota, have invented certain new and useful Improvements in Sanitary Seat Covers, of which the following is a specification.

My present invention relates generally to 10 seat covers, and more particularly to a sanitary seat cover in which the primary object is to make provision for automatically opening and closing in a manner and for a purpose which will be apparent from the following description and by reference to the accompanying drawing.

In the drawing, which forms a part of this specification,

Figure 1 is a top plan view of my improvements,

Figure 2 is a side view thereof,

Figure 3 is a top plan view of the support and closure members with the seat board removed showing the cover sections open, and

Figure 4 is a detail vertical section taken on line 4—4 of Figure 2.

Referring now to these figures, the seat board 10 proposed by my present invention has the usual opening 11 and is provided 30 centrally of its front portion with a depending bracket 12 to the lower end of which the forward end of a flexible chain or other connection 13 is attached. The upper end of this bracket has divergent arms 14 securely fastened by screws and the like 35 to the undersurface of the seat board, the rear portion of the latter of which has a transversely disposed bracing strap 16 secured thereto with ends 17 depending at the opposite sides of the seat board.

The depending ends 17 of the seat board strap 16 are pivotally connected as at 18 to connecting members or brackets 19 upstanding at the rear side portions of a seat board 45 support generally indicated at 20 and having an opening 21 below the opening 11 of the seat board 10. The seat board swings vertically with respect to the support 20 on the pivots 18, and the support is held in 50 proper position in use by hinging the same, through pivots 20^a, to the connecting members or brackets 19, the latter having lower attaching extensions 22.

The support 20 has across its forward portion, below the forward portion of the seat board 10 a transversely disposed rest bar 23

against which the forward portion of the seat board 10 engages in the lower position of the latter, and this rest bar is provided at a central point with a transverse opening 60 24 and with a guide roller 25 adjacent to the forward end of the opening 24 adapted to receive the flexible chain or connection 13 thereover in movable relation. This chain or connection 13 extends rearwardly through 65 the opening 24 of the rest bar and its rear end connects with the central portion of a cover actuating bar 26 having rearwardly diverging arms provided with longitudinal slots 27 through which slots upstand a pair 70 of pins 28. These pins are fixed to and upstand from the swinging halves or sections 29 and 30 of the cover, which sections or halves are pivoted at their forward ends at 31 upon pivot pins upstanding from the support 20 so that they swing laterally and horizontally in the same plane toward and away from one another.

The outer ends of the arms of the cover actuating bar 26 have upstanding apertured 80 lugs 32 which receive the forward hook ends of a pair of parallel coil springs 33. The rear ends of these springs are secured to pins 34 upstanding from the rear portion of the support 20 and it is thus obvious that the 85 springs 33 control the normal position of the parts and serve to shift the actuating bar 26 rearwardly whereby to hold the sections 29 and 30 of the cover in their inner contacting and effective position shown in 90 Figure 1.

On account of the springs 33 the seat board 10 is thus held in the forward upwardly inclined position shown in Figure 2 by virtue of the attachment of the flexible 95 connection 13 with the lower end of the seat board bracket 12, the seat board being thus spaced above the support 20 and its parts.

When however the seat board 10 is lowered, its bracket 12 upon moving downwardly, draws the flexible connection 13 forwardly and downwardly around the roller 25 and thus shifts the seat actuating bar 26 forwardly against the tension of springs 33. In the forward movement of this bar 26, the 105 pins 28 will be shifted outwardly in the slots 27 so that the sections 29 and 30 of the cover will be swung away from one another to the dotted line position of Figure 3 so as to uncover the opening 21 of the support 20. The 110 extent of this movement is preferably such in practice as to permit the forward por-

tion of the seat board 10 to rest upon the rest bar 23 when the cover is entirely open.

It is obvious from the foregoing that my invention promotes an arrangement which is highly desirable from a sanitary standpoint as well as one which is peculiarly effective in practice by virtue of the fact that the opening and closing movements of the cover are accomplished automatically and 10 will not fail from thoughtlessness as is so often the case where manual manipulation is depended upon.

I claim:

1. A device of the character described including means forming a seat board support having a rest bar at its forward portion and laterally spaced pivot forming members at the rear of said rest bar, and an opening, a pair of laterally and horizontally swinging 15 cover sections pivoted at their forward portions on the said pivot forming members and shiftable to uncover the opening of said support and having upstanding pins, an actuating bar having inclined longitudinally slotted arms through the slots of which said upstanding pins project, springs attached at their forward ends to the outer ends of said arms and anchored at their rear ends to the rear portion of the support, a flexible connection attached at its rear end centrally of the said actuating bar and projecting forwardly through a guide opening of the rest bar, and a seat board, having an opening, pivotally connected at its rear portion to the 20 rear portion of said support and having at its forward portion a depending bracket to the lower end of which the forward end of said flexible connection is attached.
2. A device of the character described including means forming a seat board support and having an opening, a pair of laterally and horizontally swinging cover sec- 25

tions pivoted on said support to cover and uncover its opening having upstanding pins, an actuating member in one piece having 45 slots receiving said pins and forming a movable connection with said cover sections to swing the latter in opposite directions, spring means connected to said actuating member and to the support for moving the actuating member in one direction, and a seat board having a forward depending bracket and having an opening, said seat board being pivotally connected to the support to swing vertically with respect thereto, and a flexible member having guided movement over a portion of said seat support, said flexible member having connection at one end with said depending bracket and at the opposite end with the said actuating bar to move the 60 latter in the opposite direction.

3. A device of the character described including means forming a seat board support and having an opening and a central forward roller, a seat board pivoted to the said support to swing vertically with respect thereto and having an opening above the opening of the support and a bracket depending forwardly of said roller, cover forming means shiftable on the support and 70 between the same and the seat board and movable to cover and uncover the opening of the former, spring means normally controlling the cover forming means to hold the latter in closed position, and cover actuating means to shift the cover to open position when the seat board is depressed including a single member operatively connected to the cover and having a flexible connection depending over the roller and 75 secured to said bracket.

In testimony whereof I have affixed my signature.

LARS L. FURAN.
